M. ADAMS.
Bomb-Lance.

No. 38,207.

Patented April 21, 1863.

FIG. 2

FIG. 3

FIG. 4

FIG. 1

UNITED STATES PATENT OFFICE.

MAYHEW ADAMS, OF CHILMARK, MASSACHUSETTS.

IMPROVED HARPOON.

Specification forming part of Letters Patent No. **38,207**, dated April 21, 1863.

To all whom it may concern:

Be it known that I, MAYHEW ADAMS, of Chilmark, in the county of Dukes and State of Massachusetts, have invented a new and Improved Harpoon for Catching Whales; and I do hereby declare that the following is a full and exact description.

The nature of my invention consists in providing an upper semi-revolving head to a harpoon made for that purpose, as shown by Figure 1 in the accompanying drawings, (marked B,) which rests upon a segment of a screw on either side, (marked d,) being provided with a corresponding groove within, (marked C.)

The letters *e* and *f* show a wooden pin, made to hold the part marked B in the right position with the part marked A for entering the whale.

Letter S shows a catch to hold the head B in its place.

Fig. 2 shows the position the harpoon will take when fast to a whale with a strain upon it. The wooden pin breaks and the lower head,

A, turns with the shank at right angles with the head B.

Fig. 3 shows the upper head or flukes drawn off the shank, so as to present the circular grooves, (marked C.) Letters A and B show where it rests on the points marked A of Fig. 4.

Fig. 4 is like the head of a common harpoon, with a fragment of the shank, with the addition of the two segments of screws or points marked A.

What I claim as my invention, and desire to secure by Letters Patent, is—

The application to the harpoon of a semi-revolving head resting upon segments of screws or angular pivots, causing the harpoon to turn at right angles with the semi-revolving head when fast to a whale and a strain set upon it, and then to remain fixed or coupled together.

MAYHEW ADAMS.

Witnesses:

MOSES ADAMS,
WILLIAM F. DURGIN.
